UNITED STATES PATENT OFFICE.

HUGH D. GARRETT, OF PHILADELPHIA, PENNSYLVANIA.

PISTON-HEAD.

SPECIFICATION forming part of Letters Patent No. 256,312, dated April 11, 1882.

Application filed June 24, 1881. (No model.)

To all whom it may concern:

Be it known that I, HUGH D. GARRETT, a citizen of the United States, residing at Philadelphia, in the county of Philadelphia and State of Pennsylvania, have invented certain new and useful Improvements in Piston-Heads; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My present invention relates to piston-heads for horizontal or inclined cylinders used in steam, hydraulic, and other fluid-acting machinery.

My improvement consists in the following construction and arrangement, which will be hereinafter fully described, and the points of novelty therein set forth in the claims.

Figure 1 represents an outside elevation of a piston-head to which my improvements have been applied. Fig. 2 represents a central section through the line xx of Fig. 1. Fig. 3 represents a central section taken through the line yy of Fig. 1. Fig. 4 represents a detail section taken through the line zz of Fig. 1. Fig. 5 represents a detail top view of the bearing-block in the lower portion of the piston-head, and Fig. 6 a similar view of one of the upper bearing-blocks. Figs. 7 and 8 represent respectively a side elevation and top view of the packing-rings and their adjusting levers and blocks; and Figs. 9 and 10, detail plan views, broken away, of the packing-rings. Fig. 11 represents a diagram view designed to illustrate the manner in which the weight of the piston is made to expand the packing at the top, or thereabout, of the same.

In the accompanying drawings, A represents the piston, which is preferably cast in one piece, and it is suitably cored out for reception of the packing-rings and my improved mechanism for centering the piston and automatically setting out the packing in the cylinder.

B represent levers, which have each three bearing-points, one of which bearing-points is in the lower portion of the head in the block D, another in the upper portion of head in blocks E, and the third at an interme-

diate point against bolts C. The single block D has bearings in it for the lower end of each of the levers B, and the outer surface of said block is curved to conform to the inner periphery of the packing ring or rings F, so as to present a uniform bearing against them. The blocks E are constructed with similar bearing-surfaces, and they have bearings for the upper ends of levers B. These bearings in block D and blocks E are hinge-joint bearings, and when once the levers B are inserted respectively in them and the blocks and levers put in place the walls of the piston-head on either side will serve to prevent any lateral displacement, and the inclosing socket will prevent any endwise displacement, while at the same time the levers will have sufficient vibratory movement for the purposes of my invention.

In putting on the packing-rings, which are preferably two in number, I cut each ring at the lower periphery of the piston and at the upper periphery in the manner shown in Figs. 7, 8, 9, and 10. I also insert into each of the bearing-blocks E a dowel-pin, f, arranged at one side of the block, so as to project into a suitable opening into the packing-ring F, which has the cut adjacent to the block. (See Figs. 9 and 10.) These openings for the reception of the dowel-pins f are formed between the cuts in the rings, and serve to give a positive bearing for the levers B to work against when expanding the packing at the top of the cylinder.

The bolts C are adjustable in the manner shown, and serve the purpose of centering the piston within the cylinder, to provide a bearing for each of the levers B against the head, and also to provide a means, when the packing rings F become worn at the bottom of the cylinder, for compensating for the wear by so adjusting them as to set the packing farther out from the head. The bolts C also are provided with a lock or jam nut, d, and an extension-head, d', which reaches nearly to the upper wall of the opening G, into which opening is inserted the wrench for adjusting said bolts when desired. The extension-head d' prevents the nut d from falling off the bolt into the cylinder should it by accident work loose.

The bolts C of the piston are arranged at such an angle to each other as to have a constant tendency to center the piston within the

cylinder, and the weight of the piston exerted upon the packing-rings through said bolts C and the levers B B and blocks D E E serves to expand the packing throughout the circumference of the same. Over one-third of the weight of the piston is alone exerted to expand the packing in the top of the cylinder through my arrangement of levers and supports, as will be seen from diagram Fig. 11 10 and the following formula, to wit:

Let a be one of the two supporting-points of the piston, (which are the bolts C C;) b , the center of gyration; c , the extremity of one of the levers B. Let, moreover, w denote the weight 15 of the piston; e^r , the required pressure at c :

$$y = bg - hg - hb = ik - hb \text{ the arm of the force } \frac{w}{2}.$$

$z = bl$, the arm of the required pressure e^r . Assuming the radius to be equal to unity, we have $y = ik - hb = \cos. 30^\circ - \sin. 12^\circ 30' = 0.86603 - 20 0.21644 = 0.64959$. $z = bl = \sin. 57^\circ 30' = 0.84339$.

In consequence of the equality of moments we have $\frac{w}{2} \times y = e^r z + \text{mom. } ae^r$; or, neglecting the moment $e^r a$ arising from friction, $\frac{w}{2} \times y = e^r \times z$.

Whence,

$$25 e^r = \frac{y}{z} \times \frac{w}{2} = \frac{64959}{84339} \times \frac{w}{2} = \frac{64959}{168678} w = 0.385w.$$

The blocks E have a slight movement under the packing-rings when the bolts C are adjusted. Thus it will be seen that the weight of the piston causes an increase of tension to 30 the bearing-blocks E through their connection with levers B B, thereby setting out the packing. In like manner the setting out of bolts C causes an increased tension to the bearing-blocks E by reason of their connection with levers B B. 35 The projections H, cast with the head, prevent any tendency of the packing-rings being forced down into the head at the top of the piston.

From the foregoing it will be seen that the construction and arrangement of the piston- 40 head and packing admit of the latter being set out automatically with sufficient force by the weight or gravity of the piston-head, which construction is highly desirable, as the packing is adjustable for wear, and all tendency of

the piston to stick in the cylinder through defective adjusting devices is obviated.

Having described my invention, what I claim is—

1. A piston-head provided with levers and supports, substantially as described, whereby the weight of the piston, through said levers, bears directly against the upper circumference of the packing-rings to expand the same in the upper part of the cylinder.

2. A solid piston-head provided with levers and supports, substantially as described, whereby the weight of the piston, through said levers, bears directly against the upper circumference of the packing-rings to expand the same in the upper part of the cylinder.

3. A piston-head provided with levers, supports, and centering device, substantially as described, whereby the piston is centered in the cylinder and the weight thereof utilized, through said levers, to bear directly against the upper circumference of the packing-rings to expand the same in the upper part of the cylinder.

4. A piston-head having a lever or levers fulcrumed in the lower portion of the piston and extending into the upper portion so as to rest against the packing at that point, with suitable bearings for the piston against the levers, whereby the weight of the piston is utilized to expand the packing, substantially as set forth.

5. In a solid piston-head, the combination of the levers B, bolts C, and openings G, substantially as and for the purpose specified.

6. The combination of levers B, bolts C, and blocks D E, substantially as described.

7. The combination of levers B, bolts C and their nuts d, and blocks D E, substantially as described.

8. The combination of levers B, bolts C, having the extension-heads d', nuts d, and blocks D E, substantially as described.

In testimony whereof I affix my signature in presence of two witnesses.

HUGH D. GARRETT.
